Application November 23, 1933, Serial No. 699,456

31 Claims. (Cl. 91—8)

This invention relates to the production of piled surfaces and pile surfaced materials and is particularly directed to apparatus and methods of operation adapted for the efficient production of such surfaces and surfaced materials by a process which involves positioning an adhesive-coated foundation material in an electric field and supplying pile-forming fibers thereto while in said field.

10 It has been found that the production of piled surfaces by electrically depositing fibers and the like by said process can be advantageously carried out by means of the apparatus and methods of operating which are to be described herein-after.

Among the novel features and objects of the present invention are included the use of a stream of air or other gas to disentangle the pile forming fibers and to carry them as individual suspended particles into the electric field for deposition on the surface to be piled. Further objects of the invention are to use said stream of gas to prevent or break up the "treeing" of the fibers as they approach the surface to be piled, to return for representation fibers that are not attached when first presented for deposition, to supplement the force of gravity and the electrical forces available in moving the fibers towards the surface to be piled and to provide methods of controlling the relative humidity and other gas conditions within the apparatus in which the pile forming operations are carried on.

Other objects comprise the use of auxiliary electrodes to provide efficient, safe, and convenient control of the electrical forces and the use of special electrical circuits to prevent undesirable treeing and massing of the fibers and to provide advantageous conditions as will be herein-after described.

40 The method of pile construction to which the present invention applies comprises, broadly, establishing an electric field of appreciable strength, for example, having a voltage drop of 45,000 volts between two relatively flat, parallel, electrodes three inches apart; placing a base material, e. g. cloth or paper, coated with an adhesive, within the electric field (preferably parallel and adjacent to one boundary of said field); and supplying pile-forming fibers to the region of the electric field. The fibers, initially carrying electric charges or becoming electrically charged by induction, move under the influence of the electric field and contact with the adhesive in oriented position, i. e. perpendicular to the base,

whereby only one end of each fiber is attached to the base.

The manner in which these and other objects of the invention are realized will be described in what follows, reference being had for the purpose 5 of illustration to the accompanying drawings, in which:

Fig. 1 is a diagrammatic view of a system comprising apparatus shown in sectional elevation and an electric circuit, which embodies certain 10 principles of the invention;

Fig. 2 illustrates a system, shown more or less diagrammatically, but for the most part in sectional elevation, for practicing one embodiment 15 of the invention;

Fig. 3 shows apparatus, in sectional elevation, for practicing the principles of the invention in somewhat different manner; and

Fig. 4 is a diagrammatical representation of a circuit which may be substituted in some cases 20 for the circuit shown in Fig. 1.

Referring to Fig. 1, numeral 5 designates a more or less air tight casing in which are supported two electrodes, 1 and 2, respectively, between which may be set up a strong electric field. 25 A source of energy, to be described later, is connected to electrode 1 by electrical conductor 3 and to electrode 2 by conductor 4, the latter electrode, and casing 5 also, being preferably connected to ground as shown at 6. Electrode 1 is 30 insulated from casing 5 by insulating support 7 and tube 8. Tube 8 functions both as an insulating support and as an inlet bushing for conductor 3. Electrode 2, which is shown as a screen, is supported from the sides of casing 5 35 by imperforate plate-like members 9, 9. These are free from points or projecting edges, it being desirable that no corona discharge emanate from the apparatus while it is energized.

Above electrode 2 is a basket for sifting the 40 fibers to be used in making piled surfaces. It comprises a screen 10, preferably of closer mesh than that of electrode 2, a reinforcing band 11, and a supporting sleeve 12 of flexible material, i. e. canvas, from which screen 10 depends. 45 Shaking of screen 10 is accomplished by the reciprocal movement of rod 13 brought about in turn by the turning of cam 14 by means not shown. In this embodiment of the invention, screen 10 and connected parts are connected to 50 ground by conductor 15.

The fibers are carried into the region of the electric field, that is, between electrodes 1 and 2, by air flotation; fan 16, connected to the bottom and top of casing 5 by flues 17 and 18, respec- 55

tively, being used to move the air through the apparatus. The fibers, which may be flocks cut from rayon or other fibrous material, are fed into the apparatus from hopper 19 in amounts regulatable by damper 20. As the fiber inlet is on the inlet side of fan 16 the pressures within the system may be readily regulated by means of dampers 21 and 22 so that the pressure within hopper 19 is slightly below atmospheric thus facilitating the movement of the fibers from the hopper into the air stream passing in flue 17.

The manner in which the apparatus is operated in constructing piled surfaces is set forth in the following description. The material to be piled, say a sheet of paper, is coated with adhesive and placed upon electrode 1 with the adhesive facing upwards, as shown at 23. The electrodes are now energized, the circuit indicated, to be later described, being used for that purpose. Fan 16 is started and fibers are added from the hopper 19 to the air passing in flue 17. Many fibers come from storage rather densely packed together and disintegration is necessary before they can be introduced into the electric field for deposition on material 23. The agitation provided by the fan and by passage through the flues is sometimes sufficient to break up the masses of tangled fibers, but it has been found advantageous to supplement this action by further agitation on screen 10. Some of the fibers brought to screen 10 by the air stream passing in flue 18 immediately pass through screen 10 and electrode 2 and are deposited by action of the electric field existing between electrodes 1 and 2 upon the adhesive covered material 23. Some of the fibers reach screen 10 in clumps, however, and pass through only after they have been agitated upon the surface of the screen and blown with the passing air current.

In this particular embodiment of the invention the force of gravity and the kinetic energy furnished by the air stream both augment the electric forces in pushing or pulling the fibers down upon the surface of sheet 23. The air stream must turn at 90 degrees, however, as it approaches the surface of sheet 23 in order to pass around electrode 1, as indicated by the arrows, and enter flue 17 beneath it; but this seems to be more beneficial than otherwise. The fibers that have been properly separated, charged and oriented are pulled down, definitely, to the surface and adhere to it because of the predominance of the electric forces over any sideward pull set up by the air stream. The fibers which tree or settle in loose masses over the surface of the pile are blown away by the air and carried into flue 17 to be again introduced, after further disintegration, for deposition. As pointed out above, the screen comprising electrode 2 is of coarser mesh than screen 10; for example, the former may have 6 openings to the linear inch while the latter may have 8 or more. This is to assure the ready passage of fibers through electrode 2. But sometimes long and rough fibers will build up on screen 2, necessitating the shaking or brushing of this electrode. It is to advantage to keep electrode 2 free from complications and auxiliary members and in careful alignment, parallel to electrode 1. This is best accomplished by supporting it as shown, but where shaking and the like must be resorted to, electrode 2 may be eliminated and the bottom surface of screen 10 can be made to function as the top boundary of the electric field.

Fig. 2 illustrates apparatus in which the sur-

face to be piled is held in vertical position. This construction has been found to have advantages when the fibers tend to tree between the electrodes and/or become grouped in unattached masses over the uncompleted pile. Unattached fibers can be more positively blown from a vertical surface than from horizontal surfaces such as that shown in Fig. 1. The construction illustrated in Fig. 2 also makes possible the piling of surfaces while they are moving and permits of humidity control within the apparatus.

In Fig. 2, numeral 31 designates the electrode over which material 43, which may be a flexible sheet of fabric, is caused to pass while a pile is built upon the surface thereof. Electrode 31 is maintained, preferably, at high potential and is supported by insulating means as indicated by member 37. Electrode 31 is opposed by electrode 32, made up of members 32' extending transversely and, in general, parallel to the surface of electrode 31. Members 32' are positioned from one-half to one and one-half inches apart, depending upon electrical conditions, the velocity of the air passing, and other conditions. The lower edges of members 32', the edges closest to electrode 31, are bent back or otherwise rounded to prevent corona discharge therefrom. With the edges thus rounded and spaced and carefully aligned so as to be at an equal distance from the surface of electrode 31, members 32' comprise a boundary for any electric field established between electrodes 31 and 32 that is not essentially different in its characteristics from that to be had with a flat plate. Electrode members 32' are supported, by means not shown, so their upper edges are in alignment with the bottom, and open end, of wind box 36; and air leaving the wind box is directed, in an oblique direction, by members 32' towards the surface of electrode 31. Within wind box 36 is a fiber sifting device made up of flexible sleeve 38, screen 39 dependent therefrom, and an agitating device indicated by crank 40 and connecting rod 41.

The electrodes and supports just described are enclosed in a chamber or casing 35. Casing 35 is preferably substantially air tight, but as it is difficult, although not impossible, to handle material 43 within the casing, slots are made at 42 and 44 for the entrance and exit of the material. Casing 35 is ordinarily made of electric conducting material, grounded by conductor 34, but it is advisable in some cases to make it of non-conducting material, especially that part enclosing high potential electrode 31 as indicated at a, b, c and d. Side b can be built as a door through which electrode 31 can be inspected and positioned and the insulation thereabouts can be cleaned. Electric conductor 33 connects electrode 31 to energizing means outside the casing, such as that indicated in Figs. 1 and 4. It is held in insulated relationship with wall d of casing 35 by bushing 45.

Air, or any suitable gas, is circulated through casing 35 by fan 50, connections to the fan being made by flues 51 and 52. Fibers are added to the air stream through hopper 53, the amounts added being controlled by measuring wheel 54. The characteristics of the circulating air, especially as regards humidity conditions, are controlled by adding conditioned air and releasing surplus air. Air drier than that of the atmosphere can be obtained by drawing air through drying chamber 55 which is connected to flue 51 by flues 57 and 57', control being secured by valve 58. Dehydration of the air is brought about by spreading cal-

cium chloride over trays 56 and causing the air to pass over the chloride. The air in the system may be too dry in cold weather. Humidification can be secured by drawing air into the system through spray chamber 59, water provided by spray 60 being evaporated as the air passes over baffles 61. Valve 62 permits close regulation of the humidified air admitted. Conditioned air admitted for humidity correction replaces air already in the system and this is released through valve 63. The released air carries fibers in common with the other air in circulation and these are collected in bag filter 64, removed through closure 65, and returned to hopper 53. It has been found advantageous to so regulate valves 63 and 68 (or 62) and dampers 66 and 67 that the pressure in casing 35 is held at or very slightly above atmospheric pressure. If the pressure is slightly above that of the atmosphere, air passes out slots 42 and 44, whereas at lower pressures it would enter through them. Of course, by suitable control means, gases for special purposes can be introduced into the system. If the adhesive on material 43 is accompanied by solvents having vapors which may form explosive mixtures with air, such mixtures can be avoided by adding carbon dioxide or other non-supporter of combustion in appreciable quantity. While ordinarily sparks are not present in the apparatus, improper control may cause the inadvertent presence of sparks and explosive mixtures of air and vapors are to be avoided.

The material upon the surface of which a pile is to be constructed may be a fabric ordinarily supplied in roll form as indicated by roll 70. It is stretched over guide rolls 71, 72 and 73 and over electrode 31 and slowly moved by suitable means such as rolls 75, 75 which have raised and corrugated bands at the ends thereof to grasp the sheet 43 at the edges and draw it over the other rolls and permit it to be re-rolled as indicated at roll 76. The adhesive may be put on by various methods. The method illustrated consists of the use of trough 77 with spreading edge 78 which presses upon or projects towards the fabric as it is stretched over adjustable member 79. The fibers are attached, in positions perpendicular to the surface of the fabric, for the most part, as the fabric moves over electrode 31. The piled material is then finished as may be necessary or desired. Driers and/or vulcanizers, not shown, may be provided at location 80. A beater 81 and brush 82 remove non-attached or poorly attached fibers after the adhesive has become dry. Hoppers 83 and 84 collect loose fibers that may otherwise become scattered about the operating room.

In operating the apparatus shown in Fig. 2 it is important that the fibers be separately floated in the air stream and be conducted into the electric field in this condition for deposition on the surface to be piled. The aggregates of fibers introduced through hopper 53 are broken up to a considerable extent by fan 50 which includes a wheel with paddles of simple type that is made to revolve at relatively high speed. Further disintegration is obtained with sifting screen 39 operating in the passing air stream. The air stream and burden of suspended fibers, after passing through screen 39, is divided and deflected by members 32' and is made to enter the electric field between electrodes 31 and 32 at an acute angle with the surface of material 43. The individual fibers move across the electric field too rapidly to be followed with the eye, but the re-

sult is easily ascertained. Many of the fibers reach the adhesive covered surface in oriented position; that is, perpendicular to the surface, and become fastened at one end to that surface. Some of the fibers approach the surface sidewise for lack of sufficient electric charge or some other reason, or become attracted to other fibers and tend to "tree" between the electrodes. If these unattached fibers remain over the uncompleted pile, further deposition of oriented fibers ceases; but by controlling the velocity of the air stream, a removal of such fibers is realized and deposition of fibers continues until they are so thickly packed upon the surface of the material that the material is completely hidden and a pile of appreciable mechanical stiffness results. The air velocity required to blow off unattached fibers need not be high. If blower 50 provides pressures of from one to four inches of water it is satisfactory. Too high a velocity of air in the electric field will move the charged fibers in a different direction from the direction the electric field tends to move them. But it can be readily appreciated that a stream of air moving at a properly chosen velocity and preferably at an angle which causes the air stream to augment the force of gravity will keep the region of the electric field free of uncharged and massed fibers and permit the separated and charged fibers to be deposited individually into the pile.

The control of humidity has been mentioned above. The fibers commonly used in making piles, for example, fibers of rayon, silk, and cotton and animal hairs such as those comprising wool and rabbit fur, are of small diameter and have great surface area as compared with their mass. They are, therefore, quickly and positively influenced by the moisture content of the medium in which they are suspended. The conductivity, at least the surface conductivity, of the fibers is increased by the sorbed moisture and this alters the rate of distribution of the charges upon the fibers and the manner in which they are moved and oriented in the electric field. It has been found that when the relative humidity of the air carrying the fibers is below 40 percent the fibers are noticeably slower in depositing and forming a pile. A relative humidity above 80 percent, on the other hand, tends to cause rapid deposition, but not in an orderly manner; 40 treeing and undesirable massing of the fibers result. With the means illustrated broadly in Fig. 2 and described above, the air can readily be maintained with humidity values between 45 and 75 percent of saturation, a humidity range in 55 which deposition is quite satisfactory.

In the embodiment of the invention shown in Fig. 3, the fibers are suspended in an air stream, projected upwards into an electric field, further moved upwards by action of the electric field, and deposited on an adhesive covered surface. Fan 85 for moving the air is rotated by motor 87 within a short tube 86 which is supported by adjustable members 88, 88, within casing 89. Supported upon and above tube 86 is a hood 90 with 60 a top 91 of metal screen or other suitable open mesh material. Within hood 90 is a scraping mechanism 92 comprising a plurality of contact members 93 which, upon rotation of mechanism 92, by means preferably outside casing 89 and 70 not shown, pass in rubbing contact over the inner surface of screen 91. A transverse plate 94 within tube 86 is for the purpose of preventing rotation of the air stream leaving tube 86.

An electrode 95 is suspended from cover 96 75

of casing 89 by members 97 which are mounted on springs 98. Electrode 95 can be moved downwards if sufficient force is exerted upon it to overcome springs 98, but it cannot move upwards because of stops 99. An anvil 100 with a transversely extending slot 101 is mounted on electrode 95. Within slot 101 is rapping member 102 which is dependent from rod 105 which is in turn dependent from yoke 106 which rides on cam 107. Rod 105 is vertically movable in bearings 108 and 109 and when yoke 106 drops off the high point of cam 107, spring 103 causes hammer member 104, which is positively attached to rod 105, to strike strongly upon anvil 100 and suddenly move and vibrate electrode 95.

An electric field for the depositing of fibers can be established between screen 91 and electrode 95 if either of these members is properly insulated. But it has been found more convenient 20 and more efficient and in general safer to introduce an intermediate member 110 between the members mentioned. Member 110 is shown as a screen, preferably of one-quarter inch or coarser mesh, although closer mesh can be used if the 25 screen is effectively shaken. Screen 110 is bounded by a rounded band 111 and this is supported by a plurality of members 112 and 113 which can reciprocate in bearings 114 and 115 within insulating supports 116 and 117, respectively. 30 The insulators 116 and 117 are fastened by clamping members 118 as closures over holes 119 and 120, respectively, in the walls of casing 89. Member 113 passes completely through insulator 117 and so functions as an inlet conductor for 35 electric current supplied through conductor 123 and as a connection to the agitating mechanism designated by numeral 121. A connecting link 122 of insulating material is inserted between member 113 and agitating mechanism 121 so the latter may be maintained at ground potential.

The apparatus shown in Fig. 3 is commonly used to build piles upon the surfaces of paper and textile fabrics. Roll 125 indicates a supply of cloth that is guided by rolls 126 and 127 to 45 and from the under surface of electrode 95. Rolls 128, 128, in adjustable carriage 129, position travelling cloth sheet 125 as it is coated with adhesive from a spreading device 130 similar to those used in coating so-called oil cloth. The 50 fibers or other pile forming elements are introduced into the apparatus through supply bin 131, a plunger with handle 132 being used to force the fibers downwards when necessary. Air, or gases for conditioning the air or other gaseous 55 medium within the apparatus, can be brought in through pipe 133 from any suitable supply as indicated by chamber 134.

In operating the apparatus shown in Fig. 3, the high potential side of a source of unidirectional current is connected to conductor 123, the other side being connected to conductor 124 and to ground. The devices, not shown, for drawing sheet 125 through the apparatus, are set in motion and adhesive is applied to said sheet 60 by spreader 130. Motor 87 is started and fibers are fed into the air current set up by fan 85. Scraper 92 is made to revolve. The volume and velocity of air passing through screen 91 is regulated by altering the speed of motor 87 and by 65 altering the air inlet to the fan by raising or lowering sleeve 86 with adjustable supports 88, 89. It should be pointed out that when the fibers are easily disentangled and separated by the fan, screen 91 and scraper 92 are not needed and can 70 be removed, a funnel a few inches high on top 75

of sleeve 86 being then used to direct the fibers towards the electrodes above.

Adjustments in the position of screen electrode 110 can be made through clamps 118, but in general the position of electrode 110 is definitely fixed at from two and one-half to three and one-half inches below, and parallel to, electrode 95. Changes in the strength of the electric field can be made by controlling the electric circuit conditions. The voltage difference impressed between the electrodes, as described, is from 25,000 to 10 50,000 volts and the screen electrode 110 is commonly made negative except where it is advisable to alternate the polarity of the field.

As the fibers begin to deposit on sheet 125, the means, not shown, for rotating cam 107 is set in motion to turn cam 107 at from 20 to 80 R. P. M. This causes sheet 125 to be rapped rigorously by member 102 where it passes under slot 101 and imparts a more gentle vibration to 20 all of that portion of sheet 125 which is held against the under side of electrode 95. Any fibers not attached to sheet 125 by the adhesive are thus jarred away from the pile to be recirculated. In the use of this construction and with this method 25 of operation it is an easy matter to cause the unattached fibers to leave the pile because the force of gravity pulls directly away from the pile surface and the horizontal components of the air stream forces sweep the fibers along, to the 30 sides of the apparatus, down which they are carried to the fan inlet.

It is an important object in the present invention to energize the electrodes comprised in the apparatus described above in effective manner. 35 An electric circuit for such purpose is diagrammatically illustrated in Fig. 1. A low voltage alternating current source 140, say at 220 volts and 60 cycles, is connected through a voltage control resistance 141 and a double throw reversing 40 switch 142 to a step up transformer 144. The high potential terminals of the transformer are connected to stationary shoes 145 and 146, respectively, of mechanical rectifying switch 147. The switch is turned by synchronous motor 150 in 45 synchronism with the supply current, with the result that stationary shoes 148 and 149 of the rectifier are always connected to the high potential current supply at constant polarity, that is, one shoe is always positive and the other is 50 always negative. Shoe 148 is shown connected through conductor 154 and dampening or loading resistance 152 and shunting switch 153 to ground 6 and the grounded parts of the pile forming apparatus through conductors 4 and 15. Shoe 154 is shown connected to insulated electrode 1 through conductors 155 and 3. Fibers can be 55 most effectively charged, oriented, and deposited with an electric field of constant polarity and a direct or rectified current source is preferably utilized, therefore, in energizing the electrodes. But it has been discovered that, in the use of a 60 constantly applied electric field, certain undesirable conditions become emphasized. Treeing of fibers, once begun, tends to continue and makes 65 it necessary to operate the scouring air streams and rapping devices with great diligence. Also with a constantly applied potential a sheet of insulating material being piled becomes very 70 strongly attracted to the electrode over which it is passing. It has been found that these tendencies can be checked if the polarity of the electric field is occasionally reversed. This is done in the circuit of Fig. 1, for example, by operating reversing switch 142 with an automatic device, 75

not shown, that causes the grounded side of the circuit, connected to shoe 148, to be alternately negative, for example, for two to five seconds and then positive for one-half to two seconds. 5 The high voltage electrode 1 is at opposite polarity to that of electrode 2 during the same periods, of course.

Very rapid reversals, in synchronism with the alternating current source, have been found advantageous at times. This condition is obtained 10 by shifting rectifier 147 with relation to the revolving field of synchronous motor 150 by clamping adjustable coupling 151 in a different circumferential position. In this manner electrode 1 can be maintained, say, positive and at high 15 potential, for most of the half cycle and negative and at lower voltage for a short part of the cycle. In other words, through what might be called a poor setting of the rectifier, rectification is not 20 complete and a short energization at opposite polarity follows or precedes each half wave of given polarity. "Stoss" or steep wave front impulses have also been used with good effect in some depositions. This condition is obtained by 25 opening switch 153 and inserting a condenser 151 and a spark gap 156 into the circuit as shown. The Stoss circuit will be more effective if a load 158 requiring considerable current is placed across leads 154 and 155.

30 Vacuum tube or hot cathode rectifiers can be used instead of a mechanical rectifier. Fig. 4 shows the use of a single hot cathode rectifier 159 which will permit half wave energization at constant polarity. To effect reversal of polarity 35 with this type of rectifier in the circuit, the reversing means must be placed on the high potential side of the transformer as illustrated by the use of switch 160. Switch 160, made up of conducting members 161 supported by insulating 40 member 162, will, upon rotation or upon oscillation through 90 mechanical degrees, alternately connect terminal 163 of rectifier 159, which is always negative, with high potential lead 155' and with ground. In oscillating switch 160, a longer 45 pause is made at one set of connections than at the other, thus permitting energization at one polarity for longer periods than at the other polarity. This asymmetrical timing of polarity reversals is not necessary, but has been found advantageous in connection with the present invention. 50

The apparatus and methods described above have been found to be particularly advantageous in handling pile-forming fibers of relatively great length, for example, from $\frac{1}{8}$ to $\frac{1}{4}$ inch in length and longer.

I claim:

1. Apparatus for forming a pile upon a surface by affixing attenuated materials thereto 60 comprising opposed electrode means insulated from each other, one of said electrodes being foraminous, means for establishing an electric field between said electrodes, means for establishing a gas stream through said foraminous electrode and into the electric field between said electrodes, and means for introducing pile forming material into said gas stream.

2. Apparatus for forming a pile upon a surface by affixing attenuated materials thereto comprising superposed electrode means insulated from each other, one of said electrodes being foraminous, means for establishing an electric field between said electrodes, means for establishing a gas stream through said foraminous electrode and into the electric field between said electrodes, and means for introducing pile forming material into said gas stream. 70

electrodes, and means for introducing pile forming material into said gas stream.

3. Apparatus for forming a pile upon a surface by affixing attenuated materials thereto comprising superposed electrode means insulated from each other, the upper of said electrodes being foraminous, means for establishing an electric field between said electrodes, means for establishing a gas stream through said foraminous electrode and into the electric field between said electrodes, and means for introducing pile forming material into said gas stream. 5

4. Apparatus for forming a pile upon a surface by affixing attenuated materials thereto comprising superposed electrode means insulated from each other, the lower of said electrodes being foraminous, means for establishing an electric field between said electrodes, means for establishing a gas stream through said foraminous electrode and into the electric field between said electrodes, and means for introducing pile forming material into said gas stream. 10

5. Apparatus for forming a pile upon a surface by affixing attenuated materials thereto comprising opposed electrodes insulated from one another, means for establishing an electric field between said electrodes, means for passing a web of foundation material through said field adjacent one of said electrodes, means constituting a conduit for directing a gas stream between said electrodes, means for imparting motion to the gas stream in said conduit, means for introducing pile forming material into said gas stream and means in said conduit for breaking up clumps of the pile forming material. 20

6. Apparatus for forming a pile upon a surface by affixing attenuated materials thereto comprising superposed electrode means insulated from each other, the lower of said electrodes being foraminous, means for establishing an electric field between said electrodes, means for agitating the foraminous electrode, means for establishing a gas stream through said foraminous electrode and into the electric field between said electrodes, and means for introducing pile forming material into said gas stream. 25

7. Apparatus for forming a pile upon a surface by affixing attenuated materials thereto comprising opposed electrode means insulated from each other, one of said electrodes being foraminous, means for establishing an electric field between said electrodes, means for passing a web of foundation material through said electric field adjacent the electrode opposing the foraminous electrode, means for establishing a gas stream 40 through said foraminous electrode and into the electric field between said electrodes, and means for introducing pile forming material into said gas stream. 45

8. A method of forming pile-surfaced materials, which comprises establishing an electric field between opposed electrode structures, positioning an adhesive-surfaced foundation material between said electrodes, suspending masses of pile forming materials in a gas stream, disintegrating said masses of pile forming material in said gas stream, and directing the gas stream through said foraminous electrode and into the electric field between said electrodes, and means for introducing pile forming material into said gas stream. 50

9. A method of forming pile-surfaced materials, which comprises establishing an electric field between opposed electrode structures, positioning an adhesive-surfaced foundation material between said electrodes, suspending masses of pile forming materials in a gas stream, disin- 65

- tegrating said masses of pile forming materials by passing said gas stream through a foraminous member, and directing the gas stream containing the suspended material into the region of the electric field.

5 10. A method of forming pile-surfaced materials, which comprises establishing an electric field between opposed electrode structures, positioning an adhesive-surfaced foundation material between said electrodes, suspending masses of pile forming materials in a gas stream, disintegrating said masses of pile forming materials by passing said gas stream through a foraminous member while agitating the foraminous member,

10 15 and directing the gas stream containing the suspended material into the region of the electric field.

15 20 25 30 35 40 45 50 55 60 65 70 75 11. A method of forming pile-surfaced materials, which comprises establishing an electric field between opposed electrode structures, positioning an adhesive-surfaced foundation material between said electrodes, suspending pile forming materials in a gas stream, directing the gas stream containing the suspended material into the region of the electric field, and periodically alternating the polarity of the electric field with periods of constant polarity of at least about one-half second.

20 25 30 35 40 45 50 55 60 65 70 75 12. A method of forming pile-surfaced materials, which comprises establishing an electric field between opposed electrode structures, positioning an adhesive-surfaced foundation material between said electrodes, suspending pile forming materials in a gas stream, directing the gas stream containing the suspended material into the region of the electric field, and periodically alternating the polarity of the electric field with a period substantially greater than that of commercial alternating current.

30 35 40 45 50 55 60 65 70 75 13. A method of forming pile-surfaced materials, which comprises establishing an electric field between opposed electrode structures, positioning an adhesive-surfaced foundation material between said electrodes, suspending pile forming materials in a gas stream, and directing the gas stream containing the suspended material through one of said electrode structures into the region of the electric field while agitating the electrode through which the gas stream passes.

35 40 45 50 55 60 65 70 75 14. A method of forming pile-surfaced materials, which comprises establishing an electric field between opposed electrode structures, positioning an adhesive-surfaced foundation material between said electrodes, suspending pile forming materials in a gas stream, directing the gas stream containing the suspended material through one of said electrode structures into the region of the electric field while agitating the electrode through which the gas stream passes, and periodically alternating the polarity of the electric field with periods of constant polarity of at least about one-half second.

40 45 50 55 60 65 70 75 15. In the production of piled surfaces by passing a stream of gas containing pile forming material adjacent an adhesive-surfaced foundation material positioned in an electric field, the step comprising adding a conditioning medium to the stream of gas whereby the conductivity of the pile forming material is altered.

45 50 55 60 65 70 75 16. In the production of piled surfaces by passing a stream of gas containing pile forming material adjacent an adhesive-surfaced foundation material positioned in an electric field, the step comprising regulating the humidity of the gas stream to a predetermined degree.

5 17. In the production of piled surfaces by passing a stream of gas containing pile forming material adjacent an adhesive-surfaced foundation material positioned in an electric field, the step comprising adding gaseous medium of predetermined humidity to said gas stream.

10 15 20 25 30 35 40 45 50 55 60 65 70 75 18. In the production of pile surfaces by passing a stream of gas containing pile forming material adjacent an adhesive-surfaced foundation material positioned in an electric field, the step comprising maintaining the humidity of the gas stream at a predetermined degree between about 40 percent and about 80 percent relative humidity.

15 20 25 30 35 40 45 50 55 60 65 70 75 19. A method of forming piled surfaced materials, comprising establishing an electric field between opposed electrode structures, bringing pile forming fibers into said electric field adjacent an adhesive-surfaced foundation material, and controlling the electrical deposition of the fibers by controlling the surface conductively of the fibers.

20 25 30 35 40 45 50 55 60 65 70 75 20. In the production of piled surfaces by passing a stream of gas containing electrically charged pile forming material adjacent an adhesive-surfaced foundation material positioned in an electric field, the step comprising regulating the humidity of the gas stream to a predetermined degree.

25 30 35 40 45 50 55 60 65 70 75 21. Apparatus for forming a pile upon a surface by affixing attenuated materials thereto comprising opposed electrode means insulated from each other, one of said electrodes being foraminous, means for establishing an electric field between said electrodes, means for establishing a gas stream through said foraminous electrode and into the electric field between said electrodes, means for introducing pile forming material into said gas stream, said foraminous electrode having openings adapted to break clumps of said pile forming material into individual fibers.

30 35 40 45 50 55 60 65 70 75 22. Apparatus for forming a pile upon a surface by affixing attenuated materials thereto comprising opposed electrode means insulated from each other, one of said electrodes being foraminous, means for establishing an electric field between said electrodes, means for establishing a gas stream through said foraminous electrode and into the electric field between said electrodes, means for introducing pile forming material into said gas stream, and means cooperating with said foraminous electrode for breaking clumps of said pile forming material into individual fibers.

35 40 45 50 55 60 65 70 75 23. Apparatus for forming a pile upon a surface by affixing attenuated materials thereto comprising opposed electrodes insulated from one another, means for establishing an electric field between said electrodes, means constituting a conduit for directing a gas stream between said electrodes, means for imparting motion to the gas stream in said conduit, means for introducing pile forming material into said gas stream and beating means in said conduit for breaking up clumps of the pile forming material.

40 45 50 55 60 65 70 75 24. A method of forming pile-surfaced materials which comprises establishing an electric field between opposed electrode structures, positioning an adhesive-surfaced foundation material between said electrodes, bringing pile-forming fibers into the electric field and periodically alternating the polarity of the electric field with periods of constant polarity of at least about one-half second.

45 50 55 60 65 70 75 25. A method of forming pile-surfaced materials, comprising establishing an electric field be-

tween opposed electrode structures, bringing pile-forming fibers into said electric field adjacent an adhesive-surfaced foundation material, and controlling the electrical deposition of the fibers 5 by controlling the conductivity of the fibers.

26. A method of forming pile-surfaced materials, comprising establishing an electric field between opposed electrode structures, bringing pile-forming fibers into said electric field adjacent 10 an adhesive-surfaced foundation material, and controlling the electrical deposition of the fibers by controlling the moisture content of the fibers.

27. A method of forming pile-surfaced materials which comprises establishing an electric field between opposed electrode structures, positioning an adhesive-surfaced foundation material between said electrodes, bringing pile-forming fibers into the electric field and periodically alternating the polarity of the electric field with potentials of substantially different voltage in periods of alternate polarity.

28. A method of forming pile-surfaced material which comprises establishing an electric field of periodically alternating polarity, positioning an adhesive-surfaced foundation material in said field and bringing comminuted fibrous material into the field in condition to be deposited thereon, thereby to produce a uniform pile surface

having the fibers oriented in endwise position on the adhesive surfaced material.

29. In the production of pile-surfaced material, the method which comprises feeding along a predetermined path an adhesive-coated foundation material creating an electrostatic field of alternating polarity intersecting said path and feeding comminuted fibrous material into said field in condition to be deposited thereby to produce a uniform pile surface having the fibers 10 oriented in endwise position on the adhesive surface as the foundation material is fed through the field.

30. Apparatus for forming pile-surfaced material comprising means for establishing an electric 15 field of periodically alternating polarity, means for continuously introducing into said field adhesive-surfaced foundation material and means for introducing pile-forming fibers into said field.

31. Apparatus for forming pile-surfaced material comprising means for feeding along a pre-determined path a foundation material, means for coating the foundation material with adhesive, means for creating an electric field of alternating potential intersecting said path and means 20 for introducing pile-forming fibers into said field.

HARRY A. WINTERMUTE.
